(57) **CLAIM**

The ornamental design for pediatric foot orthoses, as shown and described.

DESCRIPTION

FIG. 1 is an upper front medial perspective view of a left foot pediatric foot orthosis in accordance with my new design, a right foot orthosis being mirror image identical thereto; FIG. 2 is a lower front lateral perspective view of the pediatric foot orthosis of FIG. 1;

FIG. 3 is a top plan view thereof;

FIG. 4 is a bottom plan view thereof;

FIG. 5 is a medial side elevational view thereof;

FIG. 6 is a lateral side elevational view thereof;

FIG. 7 is a front elevational view thereof; and,

FIG. 8 is a rear elevational view thereof.
